PUMPING APPARATUS

Richard C. Mason, Tulsa, Okla.

Application October 26, 1936, Serial No. 107,511

1 Claim. (Cl. 103—45)

This invention relates to pumping apparatus, and more particularly to apparatus of that character adaptable for cementing and acidizing wells, for circulating mud fluid incidental to 5 rotary drilling of deep wells, and for other purposes for which extreme or relatively high pressure pumping is required, the principal objects of the invention being to provide an efficient, convenient and economical pumping apparatus for 10 such purposes.

In accomplishing the stated objects of the invention I have provided improved details of structure, the preferred form of which is illustrated in the accompanying drawings, wherein:

15 Fig. 1 is a perspective view of a hydraulic pump structure embodying the features of the present invention.

Fig. 2 is a vertical cross section through one 20 of the pump units particularly showing the intake and discharge valves for the operating fluid pumps.

Fig. 3 is a detail cross section on the line 3—3, Fig. 2.

Fig. 4 is a detail cross section on the line 4—4, 25 Fig. 2.

Fig. 5 is an enlarged detail cross section on the line 5—5, Fig. 2, particularly showing the construction of the valve housings, and valves at the ends of the aligned cylinders.

30 Referring more in detail to the drawings:

I designates a fluid pumping apparatus which consists generally of a frame 2 for supporting a fluid trough 3, a double series of fluid pressure and motor cylinders 4, a fluid driving pump 5 of the reversible flow type to deliver liquid to the motor cylinders for actuating the pressure cylinders, and a power take-off 6 for actuating the fluid pump.

The support 1 preferably comprises spaced 40 longitudinally arranged I-beams 7 having spaced cross members 8 which are suitably secured to the I-beams to form a firm foundation for the pumping apparatus.

The trough 3 consists of a bottom plate 9 which 45 is preferably located between the series or banks of pressure and motor cylinders and raised at one end by legs 10 supported by one of the cross members 8. Side plates 11 are suitably secured to the bottom plate and to the legs 10 for extension rearwardly to connect with a back plate 12 for forming a trough 13 for receiving cement, mud, acid, or the like, from a source of supply not shown.

Extending into the trough 13 are intakes in 55 the form of pipes 14 and 15 which are prefer-

ably mounted in T fittings 16, connecting with pipes 17 and 18 extending in parallel relation with the side frames 7 and which connect at the respective ends thereof with valve housings 19, 20, 21 and 22 through L and nipple connections 23.

The valve housings are provided in the faces thereof of receiving the pipe connections 23 with threaded openings 24, as shown in Fig. 5, the sides of which form threaded inwardly and outwardly extending bosses 25 and 26, the bosses 26 receiving the connections 23 and the bosses 25 receiving exteriorly threaded valve assemblies 27, each having bevelled valve seats 28 for seating similarly bevelled poppet valves 29 which are 10 supported in position relative to their seats by valve stems 30 operating through bores 31 in the base 32 of the valve guides. The end of the stem opposite the poppet valve is provided with a coil spring 33, one end of which seats against 15 the guide and the other end of which engages a washer held in place by a suitable retaining device 34 in such a manner that fluid entering the valve housing through the pipe connection 23 passes through ports 35 formed in the base of 25 the valve to unseat the poppet valve 29 against tension of the spring 30.

Fluid is drawn from the trough 13 into the respective pairs of valve housings 19—20 and 21—22, by means of fluid operated pump pistons, 30 the pistons being preferably operated by a motor pump which receives its operating fluid from the power fluid pump 5, as now to be described.

Oil is preferably the fluid carried by the fluid pump 5 for operating and reciprocating the 35 pistons 36 within the motors 37 each of which is mounted between two driven working fluid pumps 38 and 39 which are in turn screw threadedly engaged in threaded openings 40 of faces 41 of the valve housings. Stay bolts 42 are 40 also provided which engage with the valve housings and with spacers 44 which separate the cylinders to provide spaces for glands and gland heads 45 on the motor flanges for the passage of a piston rod later described and for holding the 45 cylinders against longitudinal movement. Flanges 43 covering the ends of the motor cylinder are also provided with stay-bolts for maintaining the flanges in sealing engagement with the motor.

The fluid pump 5 is actuated from a suitable 50 power take-off 6, which may be either from the transmission of a truck carrying the apparatus or otherwise. The fluid pump 5 is generally of a conventional reversible flow type having automatic reversing means provided to alternately 55

deliver pressure medium, such as oil, through the pipes 46 and 47 for transmission to opposite ends of the motor cylinders 37.

It should here be pointed out that the motor cylinders 37 on both sides of the trough and the connecting working medium pumps 38 and 39 are identical in arrangement and construction with the exception of size of the motor cylinders. It should be further pointed out that the series 10 of connecting cylinders are not necessarily simultaneously operated, but may be used separately under different working conditions. For example, when high speed is required and relatively low pressure permissible, the smaller of the 15 motor pumps 37 is used and the intake 15 of the larger motor pump which is not being used is preferably plugged. When the demand is for extremely high pressure the volume of working medium is reduced and the larger motor pump is 20 put in operation for slower speed, lower volume and greater power with the consequent disuse of the other series of pumps. It is apparent that banks of pumps and valves may be superimposed upon each other should the occasion 25 require greater volumes of working medium to be forced into the well than is possible with the pump shown.

As oil passes from the power fluid pump to one end 48 of the motor pump 37, the piston 36 is forced to the end 49 of the pump 37. The piston 36 is connected on a single connecting rod 50 with pistons 51 and 52 operating in the working medium or pressure pumps 38 and 39. The pistons are so arranged in the cylinders that they 30 all are in the same relative position at each position of the stroke of the motor piston. It is thus apparent that if oil is forced into the motor pump through the pipe 47 the piston 36 is forced to the left as shown in Fig. 2, drawing 40 with it the piston 52 to create a vacuum in the cylinder of pump 39 to draw fluid from the trough 13 to fill the cylinder of pump 39.

The power fluid pump 5 is provided with a reversing mechanism, not shown, which is actuated when the piston 36 reaches a predetermined 45 position, in such a manner as to cause flow of oil through the line 46 behind the piston 36 on the side 48 thereof to force the piston in the opposite direction and cause forced flow of oil reversely 50 through the line 47. As the piston 36 is moved to the right, Fig. 2, under pressure of the oil, the pistons 51 and 52 are also moved to the right to empty the cylinder of pump 38 of cement or other fluid contained therein.

55 In order to empty the cylinders, a discharge line 53 is provided having L and nipple connections 54 with the valve housings 19-22, inclusive. Valves 55 similar to the valves 27, previously described, are mounted in threaded bosses 56 in 60 the valve housings, the valves opening outwardly relative to the valve housings into the discharge line, it being apparent that the pressure generated by the oil piston, and the working medium as it is forced out of the valves 55 maintains 65 the valves 27 in closed position while the valves 55 are in open condition.

Suitable pipe connections may be added to the discharge line 53 to conduct the working medium to the bottom of the well casing, preferably by 70 a flexible hose, not shown.

When it is desired to acid treat a well to increase the flow of fluid from the oil sands by an acid which does not contain the usual inhibitors, the pump cylinders may be replaced with cyl-

inders having suitable liners of rubber or other non-corrosive substances.

The operation of an apparatus constructed as described is as follows:

Cement, or other fluid, of any consistency desired may be placed in the trough 13 by any suitable means not shown. If the conditions in the well require a great pressure for forcing cement up between the wall of the well and casing, the larger of the motor pumps is put into operation 10 by energizing the power fluid pump 5 through the power take-off 6. If conditions in the well permit of less power, greater volume may be had through the use of the smaller motor pump with its increased speed of piston reciprocation. 15 In either event, valves 57, 58, 59 and 60, Fig. 1, are provided on the pipes 46 and 47 in order to permit separate use of each series or unit of pumps, it being apparent, however, that the double series of pumps may be used to combine 20 power and speed. For example, if the pumping unit arranged at the left of the fluid pump 5, as shown in Fig. 1, is to be employed, the valves 57 and 58 are opened and the valves 59 and 60 are closed. If the pumping unit arranged to the 25 right of the fluid pump 5 is to be employed, the valves 58 and 60 are opened and the valves 57 and 59 are closed. If, however, the units are to operate in unison in response to actuation of the single fluid pump 5, the valves 57, 58, 59 30 and 60 are opened, thus providing for circulation of pressure medium between the motors of each unit and the fluid pump 5 through the branches of the pipes or lines 46 and 47 which respectively lead to opposite ends of the motor in each 35 pumping unit or series 4. Actuation of the power fluid pump causes oil or other pressure medium contained therein to flow through the pipe 46 to the end 48 of the motor pump to force the piston 36 to the opposite end of the cylinder carrying 40 with it pistons 51 and 52. As the piston 51 moves to the opposite end of its cylinder, a vacuum is created in the cylinder which draws working medium from the trough 13 into the intake pipe 17 or 18 depending upon which series of pumps is 45 being used and through the valve assemblies 27 into the cylinder 38.

As above pointed out, when the piston 36 reaches a predetermined point in the motor pump, the power fluid pump is automatically reversed 50 to force pressure medium into the side 49 of the motor pump and withdraw the pressure medium from in front of the piston on the side 48 thereof to circulate back through the power fluid pump. As the piston moves to the opposite end of the 55 cylinder under pressure of power fluid from the fluid pump, the working medium contained in the pump 38 is forced out of its valve 55 into the discharge line 53, after which it is suitably conducted to the well casing for transmission to the 60 bottom thereof under hydraulic pressure for sealing over the top of the oil sand and for contact with the side walls of the bore hole to support the casing in position.

When the apparatus is used in rotary drilling, 65 mud may be circulated from the discharge line 53 to the bottom of the well hole back to the trough 13 for reuse.

It is apparent that since the circulation of pressure medium from the power fluid pump to 70 the motor pumps is uniform, and since the cross sectional areas of the motor pump pistons vary, the piston of the larger motor pump moves more slowly than the piston of the smaller motor pump, generating, however, more power.

It is further apparent that the working fluid pumps are alternately actuated and thus generate a continuous flow of working medium from the source of supply to the bottom of the well casing.

5 What I claim and desire to secure by Letters Patent is:

A pumping apparatus including in combination with a fluid driving pump of reversible flow type 10 and means for actuating same; spaced high and low pressure pumping units each consisting of a motor having a piston, lines operatively connecting the motors of each unit with said driving pump at opposite ends of the motors to reciprocate the pistons in response to actuation of the

driving pump, a driven pump at each end of the motors having a piston connected with the corresponding motor piston and arranged to reciprocate in the driven pumps in response to reciprocation of the motor pistons by the driving pump, 5 a source of supply of material to be pumped, material supply and exhaust lines in each driven pump communicating with the source of supply and a point of delivery respectively, valves controlling flow through said supply and exhaust 10 lines to and from said driven pumps, and valves in said motor lines allowing actuation of said units separately and simultaneously.
